THOMAS FREDERICK MOORE, OF NEW YORK, N. Y.

DISPLAY DEVICE

Application filed September 20, 1923. Serial No. 663,728.

This invention relates to display devices and aims to provide a simple and convenient means for holding a display card flat and erect for display purposes.

5 It has heretofore been customary to support display cards by means of props which have frequently been hinged to the card so that they may be folded against it when not in use. Such a prop tends to prevent a bending or warping of the card in vertical direction, but does not prevent horizontal warping of the card. A card supported by such means frequently becomes warped. This not only renders it unattractive in appearance, but also prevents the prop from holding it securely in erect position.

In accordance with the present invention a display card is provided with two or more braces which extend across the back of the 20 card at an angle to each other. The braces may be hinged to the card so that they may be folded against it for transportation, and are provided with engaging means cooperating to hold both of them at right angles to the card, 25 in which position they serve to prevent warping of the card in either direction, thus holding it flat and maintaining its attractive appearance. One or more of the braces is most desirably formed so as to provide a prop to 30 hold the card in erect position. Owing to the fact that the card cannot warp, it is securely supported by the prop.

In order that the invention may be clearly understood, I will describe in detail the specific display device embodying it which is shown in the accompanying drawing, in which:—

Fig. 1 is a perspective back view of the device in display position;

40 Fig. 2 is a fragmentary perspective back view of the device in folded position; and

Fig. 3 is a fragmentary transverse section on the hinge line of one of the props, showing the parts of the device in display position.

The display device illustrated includes a display card 10 which, while comparatively stiff, is nevertheless likely to become bent or warped under the effect of heat or moisture. 50 The matter to be displayed is printed or

otherwise displayed on the front side of the card 10, that is, the side opposite to that shown in Figs. 1 and 2. A brace 11 extends longitudinally across the back of the card 10, and two braces, 12 and 12^a extend transversely across the back of the poster. All of the braces are made of stiff sheet material, such as cardboard. The brace 11 is hinged to the card 10 by means of a hinge flap 13, which is pasted or otherwise secured to the back of 60 the card. The braces 12 and 12^a are similarly hinged to the card by means of hinge flaps 14, 14^a.

The brace 12 is provided in its inner edge with a recess 15 which surrounds the brace 65 11 and permits turning the brace 11 from a position parallel to the card as shown in Fig. 2, to a position at right angles to the card, as shown in Figs. 1 and 3. The wall of the recess 15 forms a projection 16 and a notch 17 70 below this projection. The brace 12^a is similar in form to the brace 12. The free edge of the brace 11 is provided with two notches 18, 18^a which lie in the planes of the braces 12 and 12^a, when these braces are extended at 75 right angles to the card 10.

The braces 12 and 12^a may, as shown, be formed to serve as props having lower edges 19 which extend rearwardly from the lower edge of the card when extended at right 80 angles to the card and serve to hold the card in upright position.

When the device is transported, the brace 11 is folded against the card 10, and the braces 12 and 12^a are also folded against 85 the card as shown in Fig. 2. The entire device may then easily be placed in an envelope or otherwise packed for shipment.

When the card is to be displayed, the braces 12 and 12^a are turned out from the card 10. The brace 11 is then turned downwardly within the recesses 15. In this movement of the brace 11 its notches 18, 18^a first engage the projections 16, setting the braces 12 and 12^a at right angles to the card 10. 90 Further downwardly turning of the brace 11 brings its notches into engagement with the notches 17 of the braces 12 and 12^a as shown in Figs. 1 and 3. The engagement between 95 the notches holds the brace 11 and the braces 100

12 and 12^a at right angles to the card 10. When in this position the brace 11 prevents horizontal warping or bending of the card 10, while the braces 12 and 12^a prevent vertical bending or warping of the card. The braces thus serve to hold the card flat, while at the same time the braces 12 and 12^a serve as props to hold the card erect.

I wish it clearly understood that my invention is not limited to the particular form and arrangement of the parts of the illustrated device which has been described.

What is claimed is:

1. A display device, comprising in combination with a display card, two braces formed of separate pieces of material each hinged to the back of the card so that it may be folded against the card within the limits thereof or turned to stand perpendicular thereto, said braces extending at an angle to each other and each extending substantially entirely across the back of the card to serve when turned to stand perpendicular thereto to prevent bending of the card, one of said braces being formed to serve as a prop for supporting the card in upright position and being wider than the other and having a recess through which the other brace extends, and said braces being provided with cooperating means to hold them both perpendicular to the card.

2. A display device, comprising in combination with a display card, a brace hinged to the back of the card so that it may be folded against the card within the limits thereof or turned to stand perpendicular thereto and formed to serve as a prop for supporting the card in upright position and containing a recess in its inner edge, and a second brace formed of a separate piece of material, hinged to the back of the card so that it may be folded against the card or turned to stand perpendicular thereto extending at an angle to the first brace and being narrower than and passing through the recess in the first brace, said braces being provided with cooperating engaging means to hold them both perpendicular to the card, and said braces each extending substantially entirely across the back of the card to serve when turned to stand perpendicular thereto to prevent bending of the card.

3. A display device, comprising in combination with a horizontal elongated display card, a horizontal brace extending longitudinally substantially entirely across the back of the card and hinged thereto so that it may be folded against the card or turned to stand perpendicular thereto and adapted when turned to stand perpendicular to the card to prevent horizontal bending of the card, and a plurality of vertical crops hinged to the back of the card, each formed from a separate piece of material, each extending substantially en-

tirely across the back of the card and each containing in its inner edge a recess surrounding the horizontal brace, the brace and each of said props being provided with cooperating engaging means adapted to hold the brace and the props in operative position.

In testimony whereof, I have hereunto set my hand.

THOMAS FREDERICK MOORE.
